US00D654889S

(12) **United States Design Patent**
Kim et al.

(10) **Patent No.:** **US D654,889 S**
(45) **Date of Patent:** **** Feb. 28, 2012**

(54) **MOBILE PHONE**

(75) Inventors: **Chang-Hwan Kim**, Kimpo-Si (KR);
Min-Hyouk Lee, Seoul (KR);
Chang-Hwan Hwang, Seongnam-Si (KR)

(73) Assignee: **Samsung Electronics Co., Ltd.** (KR)

(**) Term: **14 Years**

(21) Appl. No.: **29/387,285**

(22) Filed: **Mar. 11, 2011**

(30) **Foreign Application Priority Data**

Dec. 17, 2010 (KR) 30-2010-0054750

(51) **LOC (9) Cl.** **14-03**

(52) **U.S. Cl.** ..... **D14/138 G**

(58) **Field of Classification Search** ..... D14/138 R, D14/138 AD, 138 AC, 138 C, 138 G, 191, D14/203.1–203.8, 496, 138 AA, 138 AB, D14/137, 147, 218, 341–347, 247–248; D10/65, D10/78, 104; D13/168; D18/7; 455/566, 455/575.1, 575.3, 575.4

See application file for complete search history.
